US00D672152S

(12) **United States Design Patent**
Shanbhag et al.

(10) **Patent No.:** US D672,152 S
(45) **Date of Patent:** ** Dec. 11, 2012

(54) **FIBROUS MATERIAL SHEET WITH PATTERNED SURFACE**

(75) Inventors: **Pramod Shanbhag**, Rocky Hill, CT (US); **V. Richard Annis**, South Windsor, CT (US)

(73) Assignee: **Suominen Corporation**, Tampere (FI)

(**) Term: **14 Years**

(21) Appl. No.: **29/398,013**

(22) Filed: **Jul. 25, 2011**

(51) **LOC (9) CL. 05-05**

(52) **U.S. CL. D5/47**

(58) **Field of Classification Search** .... D5/1-4, D5/19, 47, 53, 55-59, 60, 61, 99, 28, 49; D6/582, 583, 592, 596, 616, 622; D19/5; D24/124-126; 52/660; 112/401, 416, 439; 139/383 R; 428/32, 37, 39, 66.5, 79, 85, 428/153, 187, 190

See application file for complete search history.

(57) **CLAIM**

The ornamental design for a "fibrous material sheet with patterned surface," as shown and described.

DESCRIPTION

The sole FIGURE is a top plan view of a fibrous material sheet with patterned surface, showing our new design thereof. The thickness of the fibrous material sheet with patterned surface forms no part of the claimed design. The broken lines around the design form no part of the claim.

1 Claim, 1 Drawing Sheet

U.S. Patent

Dec. 11, 2012
